UNITED STATES PATENT OFFICE.

GEORGE H. ISLEY, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

REVERSING APPARATUS FOR REGENERATIVE FURNACES.

Application filed August 2, 1922. Serial No. 579,215.

To all whom it may concern:

Be it known that I, GEORGE H. ISLEY, a citizen of the United States, residing at Worcester, in the county of Worcester and 5 Commonwealth of Massachusetts, have invented a new and useful Improvement in a Reversing Apparatus for Regenerative Furnaces, of which the following, together with the accompanying drawings, is a specification.

10 The present invention relates to improvements in apparatus which is used to procure the reversal of a furnace of the regenerative type.

15 The invention partakes, in part, of the principles of operation which characterize the reversing apparatus forming the subject matter of my copending companion application Serial No. 268,391, filed December 26, 20 1918, and my United States Letters Patent No. 1,408,946, dated March 7, 1922, in respect of providing reversing units each consisting of bodily movable hoods and gravity acting flue closures.

25 The present invention inheres in the provision of a novel operating mechanism, acting jointly and in proper sequence on said hoods and on said closures, in such a manner as to render the latter independent of 30 engagement by the former, in the act of reversing the furnace. Other and further objects and advantages of the invention will be apparent from the following description, and from the accompanying drawings, in 35 which—

Fig. 1 is a diagrammatic view illustrating the application of the invention in two-unit form, to a regenerative furnace.

40 Fig. 2 is a longitudinal sectional view of one of the reversing units as used in Fig. 1.

45 Fig. 3 is a view in side elevation of such a unit, shown in connection with the operating mechanism therefor which constitutes the subject matter of the present invention, parts of the latter being broken away to disclose more clearly the construction thereof.

50 Fig. 4 is a fragmentary end view of the apparatus as seen from the right in Fig. 3.

55 Figs. 5, 6 and 7 are transverse sectional views on the lines A—A, B—B and C—C, respectively, of Fig. 3.

Fig. 8 is a plan view of the apparatus shown in Fig. 3.

Fig. 9 is a view in side elevation showing 55 a modification of the invention.

Like reference characters refer to like parts in the different figures.

By way of illustration merely, the invention is here shown as applied to an arrangement of reversing apparatus similar to that disclosed and claimed in my aforesaid copending application, the same involving 60 duplicate reversing units, one at each end of the furnace, and each operative with respect to five coterminous furnace flues. It is to be understood that the invention is not in any sense limited to the above or any other specific arrangement of reversing units, the present showing of same, according 65 to the arrangement of Figs. 1 and 2, being but one of a large number of adaptations.

As shown diagrammatically in Fig. 1, the regenerative furnace 1, of any well known 70 type, is provided at its opposite ends with the usual gas regenerator passages 2, 2' and the usual air regenerator passages 3, 3'. In the use of duplicate reversing units for 75 such a furnace, according to the principle set forth in my aforesaid copending application, and herein adopted for purposes of illustration, these gas and air regenerator flues at each end of the furnace have, between and in alinement with their terminals, a pair of stack flue terminals 4, 5 and 4', 5' respectively, all connecting with a common stack passage 6. Also, adjacent 80 the terminal of each gas regenerator passage 2, 2', is the terminal of a gas supply 85 passage 7, 7', thus providing at each end of the furnace a set of five coterminous 90 flues for cooperation with the two-part hood structure shown in Fig. 2.

The latter consists essentially of a pair 95 of hoods 8, 8' which are movable in unison, each being of sufficient size to bridge over and connect two adjacent flue terminals; as shown in Fig. 2, corresponding to the right hand unit of Fig. 1, the arrangement is 100 such, for each end of the furnace, that the hoods leave unbridged one or the other of the end terminals depending upon the position of the unit. It will be well understood 105 that under these conditions, with the reversing units in the positions shown in Fig. 1, the passage of air and gas through the furnace is from right to left, the two right

hand stack terminals 4' and 5' being blanked off; when said units are moved to their other positions by a left hand shifting movement, Fig. 1, the direction of the products of combustion through the furnace is reversed. In this connection, it is to be noted that in common with the aforesaid copending application, each gas supply terminal 7, 7' is equipped with a swinging closure 9, adapted, as hereinafter described, to open within the associated hood 8, and to close its terminal when the latter is left exposed by the shifting of said hood.

According to the present invention, the two hoods 8, 8 of each reversing unit are structurally united by a pair of beams 10, 10, the latter at their opposite ends, as shown in Fig. 3, being pivotally connected to parallel arms 11 and 12. The arms 11 and 12 are pivoted to a water seal or base casting 13, which has flanged openings in register with the five aligned flue terminals and which maintains around said openings a sufficient body of water to seal with the edges of closures 9, 9 and with the depending skirt 14 of each hood 8.

For obtaining the travel back and forth of each reversing unit, by a parallel rising and falling motion, as constrained by the arms 11 and 12, the present invention provides a shaft 15 which is suitably journaled in bearings provided by extension brackets of the base casting 13. Said shaft 15 is adapted to be driven through suitable gearing 16, 17 from a reversible motor 18, Fig. 3, which is caused to operate in one direction to procure the right hand movement of the reversing unit and in the other direction to procure the left hand movement of the reversing unit. To this end, the shaft 15 has formed thereon, on its left hand end, Fig. 3, a screw 19, by the rotation of which longitudinal movement is imparted to a threaded nut or block 20, between the full and dotted line positions of same, as indicated in Fig. 3. A crosshead 21 slidable in a track 22, provided by the base 13, is connected to the block 20 by means of a rigid tube 23 encircling the shaft 15, and threaded at each end into the respective members, and thus said crosshead is caused to reciprocate back and forth in response to the periodical operations of motor 18.

On a stud 24 projecting from said crosshead is journaled a roller 25 which is engageable in an open-ended track 26 formed on the adjacent pivoted arm 12. In the movement of the crosshead back and forth, to effect the translatory shifting of the reversing unit, said roller 25, for a portion of said movement, travels in the track 26, entering at the open upper end thereof, and causes arm 12 to move from dotted to full line position and vice versa, Fig. 3, thus shifting the two-part hood structure from

right to left or from left to right, as the case may be.

Referring to Fig. 3, and assuming the parts to be in extreme left hand position, as comprehended by the dotted line showing of arm 12, the initial right hand movement of the crosshead 21 brings the roller 25 into immediate engagement with the track 26, and said roller, by its pressure against the side of said track, procures the shifting of the arm 12 into full line position, it being understood that this action is accompanied by a descending and ascending movement of the roller in the track. By reason of its connection to the arms 11, 12, the reversing unit is constrained to swing over in a parallel motion, first upwardly and then downwardly, and to assist in procuring the upward component of this motion, a pair of levers 27, 27, carrying counterweights 28, 28, are pivoted on posts 29, 29 and carry rollers 30, 30 which engage with the under sides of beams 10, 10.

When the arm 12 and track 26 reach full line position, as shown in Fig. 3, the roller 25 emerges from the upper end of the track, and the continued right hand movement of crosshead 21 presses said roller against a lever 31, the latter being connected to a rock shaft 32 which carries the closure 9. This engagement between roller 25 and lever 31 rocks the cover 9 into open position and holds it there, and hence procures the unsealing of gas supply flue terminal 7 or 7' immediately following the establishment of a communication between said terminal and the adjacent regenerator terminal 2 or 2', by the superposed associated hood 8, as shown in Fig. 2.

On the opposite rotation of the motor 18, to procure left hand movement of the reversing unit, the initial travel of the crosshead 21 to the left, before roller 25 enters the track 26, allows the cover 9 to close, by gravity, thus sealing the gas supply terminal 7 or 7', which is about to be exposed. Thereupon the roller 25 enters the track 26 and procures the shifting movement to the left of the entire reversing unit, so that the two hoods thereof connect the two regenerator terminals with the adjacent stack passages, i. e., as would appear in Fig. 2 by moving the hoods 8, 8 to the left. It is to be noted that the closure 9 of each reversing unit, may, as a result of its operation in the manner above described, be utilized to regulate the flow of gas from the supply flue, by limiting the outward travel of the crosshead 21, or by changing the angular relation between said closure and its lever 31 on the shaft 32.

Referring to Fig. 9, the invention is shown in connection with a reversing unit adapted to be operated hydraulically, the actuating mechanism consisting, for in-

stance, of a pair of opposed hydraulic cylinders 33, 33, within which work a pair of plungers, connected to opposite ends of a rod 34. A sliding block 35, corresponding to the crosshead 21, Fig. 3, and travelling in ways provided by the base casting 36, is connected to and moved by a rod 37, the latter having a rigid attachment, as shown at 38, with a hydraulic plunger rod 34. The block 35 carries a roller 25 which engages, as heretofore described, in the open track 26 of arm 12, to carry the latter back and forth in the act of shifting or reversing a unit from one position to the other. In the manner also previously described, the roller 25 is engageable with a lever 31 on the shaft of flue cover 9, to move the latter into the open position illustrated in Fig. 9. The operation of the mechanism shown in Fig. 9 is substantially the same as the operation of the mechanism shown in Fig. 3, and the degree of opening of cover 9 may be varied in the same way.

I claim,

1. In apparatus of the class described, the combination with a set of furnace flues, of a shiftable reversing member cooperating therewith, an end closure for one of said flues, and a common actuating device engaging said member and said closure separately to move them in sequence.

2. In apparatus of the class described, the combination with a set of furnace flues, of a movable flue-connecting member cooperating with said flues and constrained to have a parallel motion of translation, a swinging flue closure, and a common actuating device engaging said member and said closure in sequence to impart motion thereto.

3. In apparatus of the class described, the combination with a set of furnace flues, of a movable flue-connecting member cooperating with said flues and constrained to have a parallel motion of translation, a swinging flue closure, and a common actuating device for said member and said closure having a rectilinear motion, and adapted to engage them in sequence.

4. In apparatus of the class described, the combination with a set of furnace flues, of a cooperating shiftable reversing member having a parallel motion of translation, a gravity closing flue cover, and a single

means engageable separately with said member and said cover to shift the former and to open the latter.

5. In apparatus of the class described, the combination with a movable flue-connecting element, of a flue closing element adapted to open within said connecting element and a single means engageable with both of said elements to cause them to function in sequence.

6. In apparatus of the class described, the combination with a movable flue-connecting element, of a flue closing element adapted to open within said connecting element and an actuating means, exterior to both of said elements and engageable with them separately for causing their movements in sequence.

7. In apparatus of the class described, the combination with a movable flue-connecting element of a pivoted flue cover adapted to close by gravity, and an actuating member engageable with said element to move the same and engageable with said cover to open the same.

8. In apparatus of the class described, the combination with a movable flue-connecting element, of a flue closing element adapted to open within said connecting element and a reciprocating member operating on one part of its stroke to engage and shift said connecting element, and on the remainder of its stroke to engage and control said closing element.

9. In apparatus of the class described, the combination with a movable flue-connecting element, of a swinging arm pivotally connected to said element to constrain parallel motion thereof, an open ended track on said arm, a reciprocating actuating member for said element, and a roller carried thereby which enters said track to swing said arm.

10. In apparatus of the class described, a flue-connecting element and a flue-closing element, a common actuating member for said elements having a reciprocating motion, and means for controlling the extent of travel of said actuating member in one direction to vary the opening of said flue closing element.

Dated this 26th day of July, 1922.

GEORGE H. ISLEY.
